Primary Examiner — Derrick E Holland*Assistant Examiner* — Jennifer O King(74) *Attorney, Agent, or Firm* — Merchant & Gould P.C.(57) **CLAIM**

The ornamental design for a frame for sealing cables, as shown and described.

DESCRIPTION

FIG. 1 is a front perspective view of a frame for sealing cables according to the principles of the present invention.

FIG. 2 is a back perspective view thereof.

FIG. 3 is a first side view thereof.

FIG. 4 is a second side view thereof.

FIG. 5 is a bottom view thereof.

FIG. 6 is a top view thereof; and,

FIG. 7 is a back view thereof.
